(57) **CLAIM**

The ornamental design for a waste container, as shown and described.

DESCRIPTION

FIG. 1 is a perspective view of a first embodiment of a waste container showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment of a waste container showing my new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The scoop shown in broken lines in some figures is included for the purpose of illustrating environment and forms no part of the claimed design.

The broken lines showing a knob, a pedal and an opening in the door in the figures are included to show portions of the waste container and form no part of the claimed design.

1 Claim, 8 Drawing Sheets
